UNITED STATES PATENT OFFICE.

EDWIN P. BENJAMIN, OF MINETTO, ASSIGNOR OF ONE-HALF TO THE
MINETTO SHADE CLOTH COMPANY, OF OSWEGO, NEW YORK.

MAKING GELATINE PRINTING-ROLLS.

SPECIFICATION forming part of Letters Patent No. 350,653, dated October 12, 1885.

Application filed November 20, 1885. Serial No. 183,427. (No model.)

To all whom it may concern:

Be it known that I, EDWIN P. BENJAMIN, of Minetto, in the county of Oswego and State of New York, have invented a new and useful Improvement in Making Gelatine Printing-Rollers, of which the following is a full, clear, and exact description.

Reference is to be had to the accompanying drawings, forming a part of this specification, in which similar letters of reference indicate corresponding parts in all the figures.

Figure 1 is a plan view, partly in section, of one of my improved gelatine rollers. Fig. 2 is a sectional end elevation of the same, taken 15 through the line *x x*, Fig. 1. Fig. 3 is an end elevation of the same. Fig. 4 is a plan view of a part of the gelatine plate and canvas sheet before being applied to the tubular shell. Fig. 5 is a sectional end elevation of the same, taken 20 through the line *y y*, Fig. 4.

The object of this invention is to provide gelatine printing-rollers made in such a manner that they can be used for printing continuous patterns upon cloth, paper, or other substance 25 of any desired length.

The invention consists in the method of making gelatine printing-rollers, hereinafter fully described, and also in the construction and arrangement of parts hereinafter fully described 30 and claimed.

A represents the roller-shaft, around which is placed a tubular shell, *B*. The shell *B* is slotted at one side for its entire length, and into its ends are fitted two cross-bars, *C*, which have 35 lugs *D* at one end to enter the slot of the shell *B* and hold the said shell from turning upon the said cross bars *C*. In the centers of the cross-bars *C* are formed square perforations to fit upon the squared inner parts of the journals 40 of the shaft *A*, so that the said cross-bars cannot turn upon the said shaft.

To the cross-bars *C*, upon the opposite sides of the radial line passing through the lugs *D* and the slot of the shell *B*, are journaled two 45 tubes, *E*, which are slotted longitudinally, and are provided with ratchet-wheels *F*, with the teeth of which engage pawls *G*, pivoted to the cross-bar *C* and held against the said ratchet-wheels by springs *H*, also attached to the said 50 cross-bar, as illustrated in Fig. 3. The ends

of the slotted tubes *E* are squared to receive a wrench for turning the said tubes.

I is a gelatine plate upon which the pattern is formed, and which is molded upon a sheet of canvas, *J*. The side edges of the canvas *J* extend a little beyond the side edges of the gelatine plate *I*, and have hems formed upon them, as shown in Figs. 4 and 5.

To the side edges of the gelatine plate *I* are molded strips *K*, of felt, in such positions as 60 to be pressed firmly against each other when the canvas *J* and gelatine plate *I* are drawn firmly around the shell *B*.

In forming the roller the canvas *J* and gelatine plate *I* are placed around the shell *B* with 65 the hemmed edges of the canvas *J* passed through the slot in the shell *B* and into the slots in the tubes *E*, where they are secured in place by rods *L*, passed through the said hems within the said tubes. The tubes *E* are then 70 turned to wind the edges of the canvas *J* around the said tubes and draw the said canvas and the gelatine plate *I* snugly around the shell *B*, bringing the felt strips *K* into close contact with each other. A heated knife is 75 then drawn between the felt strips *K*, which warms the adjacent edges of the gelatine plate *I* and firmly cements the said strips to each other. By this construction a practically solid gelatine roller will be formed, so that it will 80 print a continuous pattern upon cloth, paper, or other material of any desired length.

If desired, the felt strips *K* can be omitted and the edges of the gelatine plate *I* cemented to each other by drawing a heated knife between them, in the manner hereinbefore described with reference to the felt strips. It will of course be understood that any suitable composition may be used instead of gelatine.

Having thus fully described my invention, 90 I claim as new and desire to secure by Letters Patent—

1. The method of forming printing-rolls, consisting in molding gelatine on a flexible sheet to form a plate thereon, then drawing the 95 sheet tightly around a tubular shell or core until the side edges of the plate are brought together, and finally cementing said edges, substantially as set forth.

2. A core for printing-rolls, consisting of a 100

longitudinally-slotted shell, end plates or cross-bars thereon, a central shaft, and two longitudinally-slotted tubular shafts journaled in the end plates below the slot in the shell, substantially as set forth.

3. A core for printing rolls, consisting of a longitudinally-slotted shell, end plates or cross-bars therein having lugs engaging the slot in the shell, a central shaft, the two longitudinally-slotted tubular shafts journaled in the end plates below the slot in the shell, the ratchets on the ends of said tubular shafts, and pawls on the end plate engaging the ratchets, substantially as set forth.

15 4. The covering in printing - rolls herein shown and described, the same consisting in a sheet of flexible material having a gelatine plate thereon between its side edges, the said edges having hems thereon, substantially as set forth.

5. The covering for printing - rolls herein shown and described, the same consisting in a sheet of flexible material having hems on its side edges, a gelatine plate on the sheet intermediate of its hemmed edges, and felt strips on the edges of the gelatine plate parallel with said hemmed edges, substantially as set forth.

25

6. The combination, with the tubular longitudinally-slotted shell having end plates or cross-bars, and rotary shafts journaled in the end plates or cross-bars, of a flexible sheet having a gelatine plate thereon between its side edges, the projecting ends of the sheet extending through the slot of the shell into engagement with the rotary shafts, whereby, when the said shafts are rotated, the edges of the gelatine plate may be brought together, substantially as set forth.

7. The combination, with the longitudinally-slotted shell B, having cross-pieces or end plates, C, the central shaft, A, the tubular slotted shafts E E, journaled in the cross-pieces C, and means for locking the said shafts from rotation in one direction, of the flexible sheet J, having hems on its side edges and a gelatine plate, I, the hemmed ends of the sheet extending through the slot in shell B into the tubular shafts, and the rods L in the hems within the tubular shafts, substantially as set forth.

EDWIN P. BENJAMIN.
